THREE-WAY CLAMP FOR A PLAY GYM

Edwin L. Parker, Wadsworth, Ohio

Application January 20, 1955, Serial No. 34,108

Term of patent 14 years

(Cl. D54—2)

Fig. 1 is a perspective view of a three-way clamp for a play gym showing my new design, the broken lines being for illustrative purposes only,

Fig. 2 is an end elevational view, to a smaller scale, and

Fig. 3 is a side elevational view, also to a smaller scale.

I claim:

The ornamental design for a three-way clamp for a play gym, substantially as shown and described.
